FIG. 1 is a face view of a font of letters and figures showing my new design and illustrating the upper case letters, in regular and bold face, and the numerals thereof;

FIG. 2 is a face view illustrating the lower case letters thereof in regular and bold face;

FIG. 3 is a face view of the font of FIG. 1 on a reduced scale; and

FIG. 4 is a face view of the font of FIG. 2 on a reduced scale.

All the font of my design is based on an arrangement of a plurality of generally-circular inked areas overlapped, connected and otherwise arranged to create the novel, original and ornamental design.

I claim:

An ornamental design for the font of letters and figures, substantially as shown and described.
